UNITED STATES PATENT OFFICE.

LINNAEUS WINANS, OF HOOD RIVER, OREGON.

WATER-GATE.

SPECIFICATION forming part of Letters Patent No. 734,385, dated July 21, 1903.

Application filed December 2, 1902. Serial No. 133,607. (No model.)

To all whom it may concern:

Be it known that I, LINNAEUS WINANS, a citizen of the United States, residing at Hood River, in the county of Wasco and State of Oregon, have invented new and useful Improvements in Water-Gates, of which the following is a specification.

My invention relates to new and useful improvements in water-gates for use in mill-races, irrigating systems, canals, &c.; and its object is to provide a counterbalanced gate adapted to be easily opened or closed and provided with mechanism of novel construction for locking it in closed position.

Another object is to provide means for protecting the gate when open from injury by logs or other large and heavy objects approaching the same.

With the above and other objects in view the invention consists in the novel construction and arrangement of the several parts, which will be more fully hereinafter described and claimed.

In the drawings, Figure 1 is a side elevation of a flume having my improved gate therein. Fig. 2 is a section on line *x x* of Fig. 1. Fig. 3 is a plan view of the gate in position within the flume, the bridge upon said flume being broken away to disclose the gate and its operating mechanism. Fig. 4 is a view similar to Fig. 3, but showing the gate open. Fig. 5 is a section on line *y y* of Fig. 2, and Fig. 6 is an elevation of the gate with one face thereof removed.

Referring to the figures by numerals of reference, 11 are uprights, preferably braced by means of inclined beams 2 and boarded up upon their inner faces to form walls 3 of the flume. A bridge 4 is arranged upon these walls, and my improved gate is adapted to be arranged at a point below said bridge and upon the bottom 5 of the flume. The gate preferably comprises a centrally-located vertical beam 6 and parallel end strips 7, said central beam and end strips being braced by means of an inclined beam 8, as shown in Fig. 6. These beams are preferably boxed in by boards 9, suitably secured to opposite sides thereof, and as the beam 6 is of greater thickness than the end strips 7 the faces of the gate are curved or tapered toward the sides, as shown in Figs. 3, 4, and 5. The

lower end of the upright beam 6 is provided with a preferable metal stud 10, mounted in suitable bearings in the bottom 5 of the flume, 55 and a similar stud 11 is formed at the upper end of said beam and extends through the bridge 4 and into an angular head 12, fixed to said stud.

The two edges of the gate are beveled upon 60 opposite sides, respectively, as shown at 13, and these inclined faces are adapted to abut against beveled strips 14, arranged vertically on the inner faces of the walls 3 and at opposite sides of the center of the gate. These 65 strips serve to limit the movement of the gate upon its bearings and form a tight joint therewith to prevent the escape of water therebetween. When the gate is closed, it is adapted to be locked in such position by 70 means of novel mechanism. This mechanism comprises a vertical rod 15, journaled in brackets 16, secured to the inner face of one of the walls of the flume and having a series of short arms 17 extending laterally therefrom. The rod is adapted to be revolved by means of a hand-wheel 18, arranged at the end thereof at a point above the bridge 4. This rod is arranged at such a distance from the adjacent strip 14 that when the gate is moved 80 into closed position against said strip the arms 17 can be swung back of the gate and will hold the same firmly pressed against the strip. 75

The gate may be operated in any desired 85 manner, as by means of a windlass 19, mounted on standards 20, arranged on the bridge 4. A cable 21 is coiled upon this windlass and extends in opposite directions down through the bridge and over pulleys 22 to the ends of the 90 gate. These pulleys are so located that when the windlass is turned in one direction the gate will be swung open upon its pivot, while when the windlass is turned in the opposite direction said gate will be closed. If desired, 95 however, instead of employing the complicated mechanism described, an ordinary sweep may be secured to the head 12, before referred to. A guide-wall 23 is preferably located in the center of the flume and parallel 100 to the walls thereof. The end of this guide-wall is arranged at a distance from the center of the gate equal to one-half the width of said gate, and it is obvious that when the

gate is opened it will substantially appear as a continuation of the wall 23. This wall serves to protect the gate while open from injury by logs or other heavy articles floating 5 upon the water.

In operation when it is desired to close the gate either the windlass 19 is revolved or a sweep is placed upon the head 12, as the case may be. The gate is then swung open upon 10 its center, and as the resistance of the water is the same at both sides of the pivot thereof it can be easily moved until its ends come into contact with the strips 14. The rod 15 is then turned by means of its operating- 15 wheel 18, and arms 17 are swung into contact with the edge of the gate and force the same firmly against strips 14. These locking-arms 17 will absolutely prevent the reopening of the gate until they are again swung out of 20 the path thereof. I preferably provide a wear-plate 24 upon that edge of the gate which is operated upon by the arms 17.

As the distances from the central beams 6 to the ends of the gate are equal, the pressure 25 of water upon opposite sides of said gate will also be equal at all times, and it is therefore obvious that the gate can be partly opened and left in such position without the use of locking mechanism.

30 In the foregoing description I have shown the preferred form of my invention; but I do not limit myself thereto, as I am aware that modifications may be made therein without departing from the spirit or sacrificing the 35 advantages thereof, and I therefore reserve the right to make such changes as fall within the scope of my invention.

Having thus described the invention, what is claimed as new is—

40 1. In a gate of the character described, the combination with the walls of a flume, of a gate mounted upon a vertical centrally-located pivot, means upon the walls for sustaining the gate in closed position against 45 pressure in one direction.

2. In a gate of the character described, the combination with the walls of a flume, of a gate mounted therebetween upon a vertical centrally-located pivot, strips upon said walls 50 for limiting the movement of the gate and sustaining it in closed position across the flume against pressure in one direction, and means for clamping and locking the gate against said strips.

55 3. In a gate of the character described, the combination with the walls of a flume; of a gate having a pivot at a point equidistant

from the ends thereof, said pivot being located in the center of the flume, strips upon the walls of the flume adapted to be contacted 60 by and to limit the movement of the gate, a revolving rod journaled upon one of said walls, and arms thereto adapted to clamp and lock the ends of the gate against said strips.

4. In a gate of the character described, the 65 combination with the walls of a flume, of a gate therein comprising a central beam, end strips parallel thereto and at equal distances therefrom, curved faces to the gate connecting said beams and strips, said faces being 70 tapered toward each other at the ends, beveled ends to the gate, beveled strips upon the walls of the flume adapted to contact with the ends of said gate and limit its movement, and means for locking said ends upon the strips. 75

5. In a gate of the character described, the combination with the walls of a flume; of a gate pivoted in the center thereof and having its pivot located at a point equidistant from its ends, beveled ends to said gate, beveled strips upon the walls of the flume, a revolvable rod upon one of said walls, and arms 80 extending from said rod and adapted to clamp and lock the said ends against the strips.

6. In a gate of the character described, the 85 combination with the walls of a flume, of a gate pivoted at the center of the flume and having a vertical pivot at a point equidistant from its ends, strips upon the walls of the flume adapted to limit the movement of the 90 gate upon its pivot, means for clamping and locking said strips, a windlass, and a flexible connection between the windlass and the ends of the gate, whereby said gate may be swung upon its pivot. 95

7. In a gate of the character described, the combination with the walls of a flume; of a guard-wall in the center of said flume and parallel with the walls thereof, a gate pivoted between the walls of the flume and at a point 100 in alinement with the guard-wall, said pivot being vertical and arranged at a point equidistant from the ends of the gate, means for limiting the movement of the gate upon its pivot, and locking-arms pivoted to one wall 105 of the flume and adapted to hold the gate in closed position.

In testimony whereof I affix my signature in presence of two witnesses.

LINNAEUS WINANS.
